UNITED STATES PATENT OFFICE.

DANIEL KOPS, OF NEW YORK, N. Y., ASSIGNOR TO LEWIS SCHIELE & CO.,
OF SAME PLACE.

DESIGN FOR A CORSET.

SPECIFICATION forming part of Design No. 21,978, dated November 8, 1892.

Application filed June 20, 1892. Serial No. 437,367. Term of patent 14 years.

To all whom it may concern:

Be it known that I, DANIEL KOPS, of New York, in the county of New York and State of New York, have invented a new Design 5 for a Corset; and I do hereby declare the following, when taken in connection with accompanying drawing and the letters of reference marked thereon, to be a full, clear, and exact description of the same, and which said 10 drawing constitutes part of this specification and represents a side view of the corset.

This invention relates to a design for the ornamentation of a corset, with special reference to the side or hip section; and it consists 15 in the ornamentation of the corset, as shown in the accompanying illustration.

On the side of the corset is the representation of two broad bands *a b*, running from top to bottom, respectively, near the front and 20 rear edges of the side. On the waist-line is the representation of a series of narrow ribs *c*, running from the rear edge of the front

band *a* diagonally downward and rearward, terminating at the forward edge of the rear band *b*. From the forward edge of the rear 25 band *b* is the representation of a series of ribs *d*, appearing to run diagonally downward and forward in rear of the series of ribs *c* to and terminating at the rear edge of the band *a*, and above this representation of diagonal ribs 30 is the representation of narrow bands *e e*, running from the upper edge of the diagonal ribs to the top of the corset.

I claim—

The design for a corset, as herein shown and 35 described.

In testimony whereof I have signed this specification in the presence of two subscribing witnesses.

DANIEL KOPS.
